DESIGN FOR AN AIR CONDITIONING CONTROL

Arthur J. Doane, Melrose, and Edward E. Lynch,
Easthampton, Mass., assignors to General Elec-
tric Company, a corporation of New York

Application July 20, 1940, Serial No. 93,816

Term of patent 14 years

To all whom it may concern:

Be it known that we, Arthur J. Doane and Edward E. Lynch, citizens of the United States, residing respectively at Melrose, in the county of Middlesex, State of Massachusetts, and at Easthampton, in the county of Hampshire, State of Massachusetts, have invented a new, original, and ornamental Design for an Air Conditioning Control, of which the following is a specification, reference being had to the accompanying drawing, forming a part thereof, and in which

Figure 1 is a perspective view of an air con-
ditioning control embodying our new design look-
ing from above and to the right, and

Figure 2 is a perspective view of the same look-
ing from below and to the left.

We claim:

The ornamental design for an air conditioning
control, substantially as shown.

ARTHUR J. DOANE.
EDWARD E. LYNCH.
